ROCK CRUSHER

Everett N. Wood, Minneapolis, Minn.

Application December 15, 1939, Serial No. 309,387

8 Claims. (Cl. 83—53)

The present invention relates to rock crushers of the reciprocating jaw type and more particularly to those having jaws driven from a rotatable shaft upon which a flywheel is mounted.

Reciprocating jaw rock crushers, as customarily made, include a pair of relatively movable rock crushing jaws which are inclined with reference to each other. As usually made, one of the jaws is fixedly mounted with reference to the frame and the other of the jaws is mounted for oscillatory movement with reference to the stationary jaw so that stone is crushed as it moves between the jaws.

According to the usual mode of construction, the movable crusher jaw is arranged to be oscillated by an eccentric shaft which is normally provided with one or more heavy flywheels for storing kinetic energy. As rock moves through the crusher, the oscillating jaw exerts crushing forces on the rock and fractures it. Occasionally, however, an extra hard stone imposes excessive stresses with the result that the parts are excessively deflected and breakage occurs.

According to the present invention, the flywheels of a movable jaw rock crusher are rotatably mounted with reference to the rotating shaft and a resilient torque-transmitting member is interposed between the flywheel and the rotatable shaft upon which it is mounted. As a result of this construction, when the rock crushing jaws encounter an extra hard stone, the impact stresses are reduced due to the resiliency of the torque drive between the energy supplying fly-wheels and the rotatably driven shaft, and breakage of the parts is much reduced. Stated another way, in the improved construction of the present invention, a given size of part of the crusher is enabled to withstand greater stress than in rock crushers of previous construction.

It is accordingly an object of the invention to provide a movable jaw rock crusher having a rotatable drive in which resilient torque-transmitting members are interposed. It is also an object of the invention to provide a rock crusher having a fly wheel mounted upon a rotatable shaft and a resilient torque-transmitting means between the fly wheel and the shaft.

It has also been discovered that in rock crushers of the movable jaw type driven from a rotatable shaft having one or more fly wheels mounted thereon, as the movable jaws encounter an excessive hard rock, the shaft is caused to deflect. In such rock crushers having the flywheels solidly mounted upon the shaft, the deflection of the shaft tends to move the flywheel

out of its normal plane of rotation thereby inducing large strains due to the gyroscopic stability of the flywheels. Although the shaft deflection is small, it is rapidly applied due to the inherent lack of resiliency of the material being crushed, and as a consequence, the flywheels, shafts and other crusher parts have frequently been broken.

According to the present invention, such gyroscopic stresses are reduced or eliminated by 10 mounting the flywheel upon the rotatable shaft in such a way as to permit the flywheel to remain in its plane of rotation (which it has established due to gyroscopic forces), regardless of instantaneous deflection of the shaft upon which the flywheel is mounted. By mounting the flywheel in this manner, the tendency of the deflecting shaft to move the flywheel out of its established plane of rotation is eliminated and as a consequence, the flywheel continues to rotate in its established plane regardless of instantaneous deflections of the shaft on which it is mounted.

It is, therefore, an additional object of the invention to provide a rock crushing device on which the flywheel is mounted so as to permit the shaft carrying the flywheel to deflect without correspondingly moving the flywheel thereby to minimize or eliminate forces due to gyroscopic effects.

Another object of the invention is the provision of improved shielding in an oscillatable crusher for preventing the ingress of stone and dirt to certain crusher parts such as the toggle plate and toggle plate bearing.

Other and further objects of the invention are 35 those inherent in the invention herein illustrated, described and claimed.

The invention is illustrated with reference to the drawings in which Figure 1 is a side elevation partly in section of a movable jaw rock crusher made in accordance with the present invention.

Figure 2 is an end elevation partly in section of the rock crusher made in accordance with the present invention. The flywheel section of Figure 2 is taken along the line 2—2 of Figure 3.

Figure 3 is a side elevation partly in section taken in the direction of arrows 3—3 of Figure 2, the sectional portion of Figure 3 being along the line 3a.

Figure 4 is a fragmentary sketch along the line 4—4 of Figure 3.

Figure 5 is a fragmentary sectional view of a modified form flywheel useful in the present invention.

The rock crusher of the present invention in-

cludes a frame generally designated 10, which may be a unitary steel casting or fabricated from rolled steel plates. The interior cavity of the frame is of substantially rectangular cross section, defined by side walls 11-12 and end walls 13-14. The outer surface of the frame is ordinarily provided with one or more horizontal stiffening webs 16, and a plurality of vertical stiffening webs 17, in order to withstand the extremely high stresses generated in rock crushing. In the illustrated embodiment of the invention, the end wall 14 inclines outwardly at the top and is provided with an internal flange 24. At the lower edge of wall 14, there is an internal flange 18 which forms a V-notch.

Adjacent the wall 14, there is positioned a crusher jaw 20 which rests against the integrally formed flange 18 at the lower edge, and is retained at the upper edge by means of a wedge plate 22. The wedge plate is drawn inwardly in the space between flange 24 and the chamfered upper edge 19 of the crusher jaw 20 by means of bolt 23.

Within the crusher space, there is a pitman arm generally designated 30 of heavy I-beam construction. The pitman arm has an integrally formed retained notch 31 at its lower edge which serves to retain a movable crusher jaw 32. The upper edge of the jaw 32 is retained in place by means of a wedge strip 34, which is retained in place by bolt 35. At the lower rear portion of the pitman arm 30, there is provided a large V-notch 37, extending throughout the width of the pitman arm. The notch 37 is shaped to receive a chrome-manganese wear block 38 having a curved sector 39, which in turn receives the similarly curved edge of a toggle plate 40. The toggle plate extends toward the wall 13 of the crusher frame, and rests against an adjusting wedge block 42, the latter being provided with a curved notch 43 for receiving the rear edge of the toggle plate. The toggle plate is slightly curved and is provided with weakening holes 41 so that it will break when "tramp iron" or the like comes between the crusher jaws. The wedge block 42 is mounted for movement to the right and to the left as shown in Figure 1 upon pairs of rails 45 and 46, one pair of rails being mounted upon the inside of wall 11, and the other upon the inside of wall 12. The rear part of block 42 is provided with a wedging surface 50, which cooperates with a similarly shaped surface 51 of vertically movable wedging block 52. The wedging block 52 is arranged to be moved upwardly by means of an adjusting bolt 55, the latter being adjusted by mechanism generally designated 60 having an adjusting handle 61. As the handle 61 is moved, the bolt 55 is drawn upwardly with the result that block 52 is likewise drawn upwardly and due to the slanting surface 51 imposes upon the block 42 a movement to the left as shown in Figure 1. The wedge block 42 in turn moves the toggle plate 40 to the left and as a result swings the lower edge of the toggle arm 30 to a position closer to the stationary crusher jaw 20.

The entire lower end of the pitman arm 30 is drawn in the direction of arrow 63 by means of a heavy spring 65, which is attached to the pitman arm by means of bolt 66. The right-hand end 67 of the spring is attached to the hooked member 68 while the left-hand end 69 of the spring is attached to the member 70, the latter being mounted for adjustable movement by means of bolt 71 and nuts 72. Thus, as the bolt 70 is drawn to the right as shown in Figure 1,

the spring 65 is compressed and a force in the direction of arrow 63 is imposed upon the lower end of the pitman arm 30.

Referring to Figures 1 and 2, it will be noted that the side members 11 and 12 of the frame extend upwardly and form bearing pads generally designated 80 and 81 in which there is rotatably mounted a shaft generally designated 85. In each of the bearing pads, there is a pair of tapered roller bearings generally designated 86. The bearings 86 are held in a bearing retainer 87 and are encased against the intrusion of dust by means of a cap 88. Between the bearing pads 80 and 81, the shaft 85 is provided with an eccentric portion 90, on each end of which there is mounted another tapered roller bearing 91. The bearing 91 is held within a bearing retainer 92, which is in turn bolted to the upper hollow portion 93 of the pitman arm. The upper end of the pitman arm is thus moved due to the eccentricity of the shaft 85 and the movable crusher jaw 32 is accordingly displaced toward and away from the stationary jaw 20.

It will be noted that the space between bearings 86 and 91 is filled by a flange collar 94 and a collar 94a which are separate pieces. By making these parts separate, each is concentric. They may be made inexpensively as compared with the cost of a single piece having an eccentric portion at 94.

The outer extending ends 108 and 109 of the shaft 85 are provided with flywheel assemblies generally designated 102. The assemblies 102 include a hub portion generally designated 106, which is keyed to the shaft 85 at 107 and an outer flywheel member generally designated 104. The hub 106 has a bearing surface 108 upon which the hub portion of the flywheel member 104 is rotatably mounted. The hub 106 has an outwardly extending flange 109, which is curved over as shown at 110, where it meets a circular flange 111 on the web 112 of the flywheel portion 104.

Referring to Figure 3, it will be noted that the web 112 of the outer flywheel part 104 is provided with eight lugs 113, which extend from near the inner circular flange 111. The lugs 113 are spaced apart from each other and form a cavity. The hub part 106 also has sets of lugs 116, four in number, which are formed integrally upon the portion 109 of the member 106. The lugs 113 (of the flywheel part 104) and the lugs 116 (of hub part 106) overlap when assembled, the lugs 116 being assembled so as to fall in the cavities defined by the lugs 113. The width (thickness) of the lugs 116 is less than the width of the cavity between the lugs 113, and the intervening space is filled with rubber blocks 119. The rubber blocks are preferably made of rubber having a hardness of from 50 to 100 as determined by a durometer, which hardness approximates that of tread rubber of automotive tires. The blocks are preferably molded with holes 120, and are made slightly over-size so that they are initially under slight compression in their assembled condition. The hub portion of the outer flywheel member 104 is provided with a hole 108a held upon the bearing surface 108 of the inner flywheel member by means of a plate 122 and cap screws 123.

In fitting the flywheel part 104 upon hub 106, care is taken to provide a fit so that the flywheel may, under certain conditions, run in a plane which is not at right angles to the axis of shaft 85. The least expensive way of accomplishing this is to machine the hub part 108 cylindrical and to provide hole 108a in the flywheel with a slight

taper running throughout most of the length of the hole. Thus, near the end 125 the hole 108a may have a contact fit with cylindrical bearing part 108 for length of about $\frac{1}{2}$ to 1 inch, and may then taper outwardly so that near the point 126 there is a clearance of from one-half to three thousandths of an inch every inch of diameter of hub 108, the amount depending upon the calculated deflection of shaft 85 under most extreme conditions of loading. The portion 104 of the flywheel assembly is thus permitted to pivot about the tight fitting part 125 as will be explained below. In the drawings the taper of hole 108a is greatly exaggerated for purposes of illustration.

The collar 122 serves to hold the portion 104 of the flywheel on the hub 108 and initially to place the rubber blocks 119 in a state of compression. The rubber blocks 119 react against the flywheel 104 and normally hold it against collar 122 and hence in a plane at right angles to the axis of shaft 85. A space of about $\frac{1}{8}$ to $\frac{1}{4}$ inch is allowed between the flange 110 of hub 108 and the flange 111 of flywheel member 104 so as to permit rocking motion of the latter.

During rock crushing operation of the device, rock is dumped into the crusher between the stationary jaw 20 and the movable jaw 32, and the diameter of each rock particle is reduced as the rock passes downwardly until it passes through the nip portion 21 between the lower edge of the crusher jaws. In the event an excessively hard stone such as a granite boulder or a quartzite block should enter the crusher, the movement of the jaws is momentarily much slowed down or even momentarily stopped, and as a result the rotatable shaft 85 is likewise momentarily slowed down or stopped. The parts are all placed under heavy strain and being elastic, they deform under the force induced by the heavy flywheel.

The flywheel, however, may overrun slightly as it compresses one set of the rubber blocks 119 against the lugs 113 and consequently, there is gradually built up a force sufficient to crush the rock. The rate of application of stress is therefore distributed during the time that the rubber block is being compressed and the impact load accordingly greatly decreased.

As the stress increases in the crusher jaws, the shaft 85 and other parts, the portion 90 of the shaft, between bearings 80 and 81 is deflected laterally, thus producing a slight bowing of the shaft, and consequently, the outer ends 109 and 110 are likewise deflected as the shaft assumes the "bowed" condition. All the while this is happening, the shaft and flywheels are rotating and due to gyroscopic forces, the flywheels 102 tend to remain in the plane in which they were rotating. In ordinary crushers in which the flywheels are fixed on the shaft, there is a severe strain set up as the bowing shaft tries to move the flywheels out of this established plane of rotation, since there are combined the large instantaneous torque and bending forces in the shaft.

In the present invention, however, the flywheels 102 are mounted so that they may, without undue force, be moved out of their normal place at right angles to the shaft 85, due to the clearance between the bearing portion 108 of the hub 106 and the hole 108a of the outer flywheel portion 104, and due to the provision of clearance at the surface 126. As a consequence, as the shaft 85 deflects under load, it does not move the flywheel parts 104 out of their established planes of rotation, even though the flywheel parts 104 give

up their velocity energy (as torque) to the shaft, through the rubber block connection. Hence, the instantaneous loading and flexing of shaft 85 does not impose excessive stresses upon the web 112 and upon the shaft near hub 106 as would be the case if the flywheels 102 were solidly connected to the shaft 85.

As the rock fractures, the load upon the crusher is released, and crusher jaw 32 then being free to move toward the stationary jaw 20. As a result, the stored-up energy in the rotatable shaft, which is bowed due to crushing forces and also twisted due to the torsional load thereon, and the stored-up energy of all of the remaining stressed parts of the crusher, including that stored in the rubber blocks 119, are all instantaneously released, and the shaft 85 hence tends to overrun the flywheel part 104. As the shaft thus overruns, the lugs 116 tend to compress the opposite set of the rubber blocks 119, and the instantaneous overrun of the shaft 85 is thus gradually decreased without imparting excessive forces on the various parts.

Figure 5 is an illustration of the modified form of flywheel construction in which a spherical bearing is provided between the hub portion and the flywheel portion in order to facilitate operation of the flywheel in a plane which is not at right angles to the shaft 85. In the modified form of the invention, there is mounted upon the shaft 85 a hub portion generally designated 130, consisting of two outer flange plates 131-131, which are somewhat similar to the hub portion 106 with the extending flange part 109-110 of the type shown in Figure 2. Between the parts 131-131, there is positioned an inner hub 132 having a spherical surface 133. The three hub parts, namely, the part 133 and the outer parts 131-131 are held together in immovable relationship by a plurality of through bolts 135 and the three constitute a unit which is keyed to the shaft by means of key 137.

Each of the outer portions 131 is provided with an outer marginal flange 138 having an inturned portion 139 at its edge, and an inner flange 140. In the space between the outer and inner portions 139 and 140 respectively, there is an annular space in which there are positioned a plurality of radially extending lugs 141 similar to the lugs 116 of the flywheel shown in Figures 2 and 3. Journalled upon the spherical seat 133 and held between the portions 131 there is mounted an outer flywheel member generally designated 150. This member is divided along the line 151 for purposes of assembly, and the divided parts 152 and 153 are held together by a plurality of bolts 154.

The part 153 is provided with an inner flange 154 and an outer flange 155, and the part 152 is provided with an inner flange 157 and an outer flange 158. The annular space between the inner flange 154 and the outer flange of part 153, and the similar annular space between the inner flange 157 and the outer flange 158 of part 152 is sectorized by a plurality of webs 160. The webs 141 of the outer members 131 are positioned so as to fall within the spaces divided by the webs 160 of the flywheel portion 150 in the same manner as that shown in Figure 3, and the intervening spaces filled with rubber block in the fashion shown in Figure 3.

The member 152 extends outwardly and forms webs or spokes at 163 and is provided with an outer flywheel face 164, which may, if desired, be crowned at 165 to receive a driving belt.

In assembling the flywheel shown in Figure 5,

the spherical hub portion 132 is first inserted into the spherical bearing hole of part 152. Then the part 153 is assembled against part 152 and the bolts 156 are drawn tight. This holds the outer portion 150 of the flywheel on the spherical seat 132, but in the thus assembled condition, the outer flywheel member 150 is movable under light force upon the spherical bearing part 133. The rubber blocks are then inserted in the cavities formed by webs 141 of the inner flywheel member 150, and the outer parts 131—131 are arranged so that their webs 160 will come between the pairs of rubber blocks. The bolts 135 are then drawn tight so as to place the rubber blocks in an initial state of compression. The axial dimension of the member 132 is made sufficient that clearance of $\frac{1}{8}$ to $\frac{1}{4}$ of an inch will be provided at the division line 168 between the outer flywheel members 131 and the inner flywheel member 150.

As thus assembled, the flywheels part 150 is connected for torque transmission with the hub assembly 130, but part 150 may be deflected out of the plane at right angles to shaft 85. As the flywheel rotates, it will establish (or tend to maintain) its plane of rotation at right angles to the shaft 85. During rock crushing, as previously explained, when the shaft 85 is laterally deflected and thereby assumes a somewhat bowed condition the spherical seat 133 of the inner member will rotate angularly with reference to the outer flywheel member 150, even though at the same time member 150 produces a rotative torque upon the members 131—131, and consequently upon the shaft 85 by virtue of the rubber block connections between the flywheel members 150 and 130. Due to inherent gyroscopic forces upon the flywheel member 150, it will continue to rotate in its established plane of rotation regardless of deflection of shaft 85, but at the same time, will deliver kinetic energy (as a rotative torque) to the shaft 85 through the flexible rubber block connection.

In the crusher shown in Figure 1, there is provided a rock shield member 170, which extends upwardly from the frame portion 13 to within a short distance of the rear face of pitman arm 30 as shown at 171. It is usually desirable to provide a flexible tip such as tip 172 between the rock shield 170 and the pitman arm. This may desirably be made of flexible belting or the like. The rock shield prevents small chips of rock and dust from working down into the space behind the crusher jaws and interfering with the action of the toggle plate 40 in wear block 38, at which place the bearing pressures are exceedingly high and the bearings must therefore be maintained in as good condition as possible in order to prevent undue wear. The exclusion of dust and rock chips also facilitates free action of the wedge blocks 42 and 52 for adjusting the toggle plate 40.

It will be noted that due to the fact that the contact seat between the toggle plate and wedge block 42 is at an elevated position as compared with the contact seat between the toggle plate and the wear strip 38 of the pitman arm, the lower end of the pitman arm 30 and the adjacent portion of the crusher jaw 32 is caused to move toward the stationary jaw 20, and thus produces a crushing action at the lower or "nip" portion of the jaws when the eccentric portion 91 of the shaft 85 is moving through the sector of rotation defined by arrow 180, even though at the same time, the upper portion of the pitman arm is moving upwardly and away from the stationary

crusher jaw. During the other sector of the turn generally indicated by the arrow 181, the upper portion of the crusher jaw 32 is moved towards the upper portion of the stationary crusher jaw 20, and thus produces a crushing action on the large stones at the upper or "entrance" portion of the jaws. In this way, the crushing action is distributed throughout a considerable portion of each complete revolution of the crusher jaw, and the working forces upon the crusher jaw are accordingly decreased for a given output of the crushed jaw. This arrangement is a desirable feature of the invention inasmuch as the capacity of the machine for a given stress upon the crusher parts is accordingly increased.

Entirely by way of example and without any intention of limiting the broader aspects of the invention, it may be stated that in a crusher having a jaw width of 24 inches and a maximum opening (distance between the jaws) of 10 inches (known as a 10 inch x 24 inch crusher), the shaft 85 is made approximately 5 and $\frac{1}{16}$ inches in diameter on the ends 100 and 101, and is approximately 7 inches in diameter at the eccentric portion 91, the eccentricity being approximately $\frac{5}{8}$ of an inch. A crusher of this type may desirably be provided with flywheels having a total weight of 1 ton each and an outside diameter of approximately 50 inches, although 36 inch flywheels may also be used.

When operating at a speed of approximately 250 R. P. M. and provided with an adequate power supply (approximately 75 horsepower), it is possible to crush approximately 20 cubic yards of hard granite rock per hour and reduce the size of the stone from an average of 10 inches maximum dimension to 1 inch maximum dimension.

Many obvious variations may be made without departing from the spirit of the invention illustrated, described and claimed. Thus, in respect to the rubber torque-transmitting blocks, the rubber may be positioned nearer the rim than illustrated, or may be made of different size than that illustrated. Likewise, the number of blocks used may be less than 8 or more than 8 depending upon the amount of load carried and the type of rubber used. Likewise, the dimensions of the crusher may be widely varied to satisfy the particular conditions under which the crusher is used, and the size of the flywheels, the horsepower input and other factors may be varied in any instance to suit the exigencies of the situation in which the crusher is used.

Likewise, either the resilient torque transmitting arrangement or the suggested arrangements permitting the flywheel to run in a plane not at right angles to the shaft may be used in the absence of the other since each contributes an independent stress reducing effect in addition to their combined restress reducing effect.

These and other variations will be apparent to those skilled in the art and are intended to be within the scope of the invention herein claimed.

What I claim is as follows:

1. A reciprocating jaw crusher comprising a frame, a stationary crusher jaw mounted on said frame, a jaw mounted for movement relative to the frame and rotatable shaft means mounted on the frame and connected to the movable jaw for moving the jaw toward and away from the stationary jaw, a flywheel mounted on said rotatable shaft for rotation relative thereto and for slight movement out of a plane at right angles to the axis of said shaft, said flywheel

being formed with walls defining a cavity, a protrusion formed on the shaft extending into said cavity and rubber torque transmitting blocks between the protrusion and the cavity wall for transmitting torque forces from the protrusion to the walls.

2. A reciprocating jaw crusher comprising a frame, a stationary crusher jaw mounted on said frame, a jaw mounted for movement relative to the frame and rotatable shaft means mounted on the frame and connected to the movable jaw for moving the jaw toward and away from the stationary jaw, a flywheel mounted on said rotatable shaft for rotation relative thereto and for slight movement out of a plane at right angles to the axis of said shaft, said flywheel being formed with a plurality of projections extending outwardly from its axis of rotation, said projections being spaced from each other, projection means on the shaft positioned to extend outwardly between the projections of the flywheel, and rubber blocks mounted in the space between the shaft projection means and the flywheel projections for transmitting torque forces between the shaft and flywheel.

3. A reciprocating jaw crusher comprising a frame, a stationary crusher jaw mounted on said frame, a jaw mounted for movement relative to the frame and rotatable shaft means mounted on the frame and connected to the movable jaw for moving the jaw toward and away from the stationary jaw, a flywheel mounted on said rotatable shaft for rotation relative thereto and for slight movement out of a plane at right angles to the axis of said shaft, said flywheel being formed with a hub and web extending from the hub toward the rim; a circular flange extending axially with reference to the web and spaced from the hub, a plurality of spaced lugs on the web and extending axially with reference to the flywheel, said lugs dividing the space between the hub and circular flange into sectors, and a part formed on the shaft extending parallel to the flywheel web for substantially enclosing the space between circular flange and the hub, lugs on said part extending into the sector and rubber blocks in the enclosed sector spaces between the flywheel lugs and part lugs.

4. A reciprocating machine for repeatedly applying heavy pressure to work undergoing treatment comprising a frame, a reciprocating work member mounted on said frame for movement relative thereto, a support on the frame for holding the work undergoing treatment, a shaft rotatively mounted in spaced journals on the frame, said shaft being provided with an eccentric portion between the journals, a movable portion of said reciprocating work member being rotatively connected to the eccentric portion of the shaft, a

flywheel mounted on the shaft for slight movement from a plane at right angles to the shaft whereby the flywheel may maintain rotation in an established plane when the shaft bends transversely while rotating under load, said flywheel also being mounted for rotative movement relative to the shaft said flywheel being formed with a hub and web extending from the hub toward the rim; a circular flange extending axially with reference to the web and spaced from the hub, a plurality of spaced lugs on the web and extending axially with reference to the flywheel, said lugs dividing the space between the hub and circular flange into sectors, and a part formed on the shaft extending parallel to the flywheel web for substantially enclosing the space between circular flange and the hub, lugs on said part extending into the sector and rubber blocks in the enclosed sector spaces between the flywheel lugs and part lugs.

5. A reciprocating jaw rock crusher comprising a frame, a rock crushing jaw mounted in stationary relationship on said frame, a shaft rotatably mounted on said frame, said shaft having an eccentric portion, another jaw mounted on said frame for movement relative thereto and connection means between the jaw and said eccentric portion of the rotatable shaft for reciprocating the movable jaw from the shaft as the shaft is rotated, a flywheel mounted on the shaft for rotation relative to the shaft and for slight movement out of a normal plane at right angles to said shaft, and torque transmitting means connecting the flywheel and shaft including a shaft projection extending outwardly from the axis of the shaft adjacent the flywheel and a cooperating flywheel projection positioned on the flywheel so as to be in the plane of rotation of the shaft projection and a tough rubber block between the flywheel and shaft projections for transmitting torque from one to the other.

6. The apparatus of claim 5 further characterized in that the space between the projections of the shaft and flywheel is substantially enclosed and said substantially enclosed space filled by the rubber block.

7. The apparatus of claim 5 further characterized in that the space between the projections of the shaft and flywheel is substantially enclosed and said substantially enclosed space is filled by the tough rubber block, and further characterized in that said block is provided with an aperture for facilitating compression.

8. The apparatus of claim 5 further characterized in that said tough rubber block has a hardness of 50 to 100 as determined by a durometer.

EVERETT N. WOOD.
